Primary Examiner — Darlington Ly(74) *Attorney, Agent, or Firm* — Studebaker & Brackett PC(57) **CLAIM**

The ornamental design for an automobile exterior front trim, as shown and described.

DESCRIPTION

FIG. 1 is a top, front, and left side perspective view of an automobile exterior front trim showing our new design; FIG. 2 is a front and left side perspective view thereof; FIG. 3 is a front and right side perspective view thereof; FIG. 4 is a front elevation view thereof; FIG. 5 is a left side elevation view thereof; FIG. 6 is an enlargement of FIG. 1 showing a partial top, front, and left side perspective view thereof; FIG. 7 is an enlargement of FIG. 2 showing a partial front and left side perspective view thereof; FIG. 8 is an enlargement of FIG. 3 showing a partial front and right side perspective view thereof; FIG. 9 is an enlargement of FIG. 4 showing a partial front elevation view thereof; and, FIG. 10 is an enlargement of FIG. 5 showing a partial left side elevation view thereof. The even broken lines showing the automobile are provided for the purpose of illustrating environmental structure and forms no part of the claimed design. The dash-dot broken line in the drawings illustrate a boundary of the claimed design and forms no part thereof.

1 Claim, 10 Drawing Sheets(56)
